United States Patent Office

Des. 181,184
Patented Oct. 15, 1957

181,184

FRANKFURTER TOASTER

John J. Cataldo, Newark, N. J.

Application June 2, 1955, Serial No. 36,338

Term of patent 14 years

(Cl. D81—10)

Fig. 1

Fig. 2

Fig. 3

Fig. 4

Fig. 5

Figure 1 is a side elevational view of a frankfurter toaster or similar article, showing my new design;

Figure 2 is a top plan view thereof;

Figure 3 is a bottom view thereof;

Figure 4 is a right end view thereof; and

Figure 5 is a left end view thereof.

I claim:

The ornamental design for a frankfurter toaster or similar article, as shown.
